DESIGN FOR A BOTTLE OR SIMILAR ARTICLE

Ferdinand S. Barbiers, Lancaster, Ohio

Application May 29, 1940, Serial No. 92,691

Term of patent 3½ years

To all whom it may concern:

Be it known that I, Ferdinand S. Barbiers, a citizen of the United States of America and a resident of Lancaster, in the county of Fairfield and State of Ohio, have invented a new, original, and ornamental Design for a Bottle or Similar Article, of which the following is the specification, reference being had to the accompanying drawing, forming a part thereof.

I claim:

The ornamental design for a bottle or similar article, substantially as shown.

FERDINAND S. BARBIERS.
